US00D844768S

(12) **United States Design Patent** (10) **Patent No.:** **US D844,768 S**
(45) **Date of Patent:** **** Apr. 2, 2019**

(54) **WATER HEATER TOP CAP ASSEMBLY**

(71) Applicant: **Rheem Manufacturing Company**,
Atlanta, GA (US)

(72) Inventors: **Timothy Scott**, Tallassee, AL (US);
William Jason Hall, Prattville, AL
(US); **Gregory Welk**, Prattville, AL
(US); **Scott Cline**, Columbus, OH (US);
Timothy Rothwell, Columbus, OH
(US)

(73) Assignee: **RHEEM MANUFACTURING
COMPANY**, Atlanta, GA (US)

(**) Term: **15 Years**

(21) Appl. No.: **29/616,433**

(22) Filed: **Sep. 6, 2017**

(51) LOC (11) Cl. **23-03**

(52) U.S. Cl.
USPC **D23/386**

(74) *Attorney, Agent, or Firm* — King & Spalding LLP

(57) **CLAIM**

The ornamental design for a water heater top cap assembly,
as shown and described.

DESCRIPTION

FIG. 1 is a front perspective view of the new design for a
water heater top cap assembly;

FIG. 2 is a back perspective view thereof;

FIG. 3 is a bottom plan view thereof;

FIG. 4 is a top plan view thereof;

FIG. 5 is a front elevation view thereof;

FIG. 6 is a back elevation view thereof;

FIG. 7 is a right side elevation view thereof;

FIG. 8 is a left side elevation view thereof; and

FIG. 9 is a front perspective view of the water heater top cap
assembly installed on a water heater; and,

FIG. 10 is a back perspective view of the water heater top
cap assembly installed on a water heater.

The broken lines shown represent portions of the water
heater top cap assembly and environmental portions of the
water heater that form no part of the claimed design.

1 Claim, 10 Drawing Sheets
